CHARLES L. SKELLEY, OF NEW YORK, N. Y.

SAFETY RAZOR.

Application filed July 3, 1925. Serial No. 41,370.

My invention relates to razors and more particularly to a safety razor having a guarded blade which may be stropped without removal from the supporting handle.

The hoe type of razor has met with considerable popular favor but one draw-back with the constructions which are most popular on the market is that it is necessary either to throw away the blade after a few uses or to remove it from the razor handle and hone or strop it in a separate apparatus. For the sake of economy, as well as to avoid the nuisance of having to replenish one's supply of fresh blades, a safety razor should be so constructed that the blade may be repeatedly used and easily stropped and honed. Moreover, the standard razor blade may be made of the best obtainable steel and in accordance with the highest standards of workmanship, because the blade is to last for a long time and the average purchaser is willing to pay the cost price of such a superior article. On the other hand, the manufacturer of thin wafer blades, intended to be used a few times and then thrown away, faces a keen competition that detracts from his ability to employ the best of materials and workmanship. In fact, it is to his interest that the blade shall have but a short life before a new set of blades must be purchased. There is therefore a popular demand for a safety razor of a better quality than now ordinarily obtainable on the market. Moreover, in a razor which requires one to remove the blade from its holder in order to strop it, obviously does not satisfy all of the requirements, since this involves using a separate contraption for holding the blade during stropping. Another shortcoming of most of the automatic stropping razors is that the blade in stropping rides along the strop under limited mechanical pressure whereas a manually stropped razor or blade is pressed on the strop as heavily as operator desires, obviously requiring fewer strokes and less time to make the edge keen.

Various attempts have been made to provide a hoe type of safety razor which may be stropped, but none has been devised which meets the chief objections had against this form of razor. Such a device should be simple in its construction and operation, and the guard used to protect the blade should be so located and arranged that it may re-

main attached to the blade and yet permit stropping the latter. The blade should be so mounted on its handle that it may be easily adjusted to either a shaving or a stropping position and secured there, without unnecessary attention on the part of the operator. The device should be fool proof and ready to use at all times.

It is accordingly the main object of my invention to provide a simple and economically constructed safety razor which has a standard steel blade properly protected by a guard and so arranged that the blade may be used in hoe-like position for shaving or moved to a stropping position without removal of either the blade or the guard from the handle.

It is a further object to provide a razor of this type with a blade holding and locking mechanism which may be manually adjusted to secure the blade rigidly in either of its two operative positions and which permits the blade to be quickly shifted as desired.

It is a further object to provide a safety razor with a guard for the blade which is so mounted on the blade that it will be held normally in a correct position relative to the blade edge for shaving, but may be readily shifted to a non-guarding position and permitted to swing idly while the blade is being stropped, honed or dried.

It is a still further object of the invention to provide a guard for the razor blade which is so mounted thereon that as the blade wears down in size, the guard automatically assumes a proper position relative to the edge and the razor is always in correct arrangement for efficient service.

With these and other objects in view as will be apparent to one skilled in the art, my invention resides in the combination of parts set forth in the specification and covered by the claims appended hereto.

In accordance with one aspect of my invention, I propose to provide a safety razor which has a blade movably mounted on a handle and so arranged that it may be held in a hoe-like position for shaving or in a suitable stropping position, and preferably one in which the blade is substantially radial to the center line of the handle. I also provide a razor blade with a guard which is so mounted thereon that the guard bar may be located laterally of the blade as a safety

arrangement and to protect the blade edge when the razor is not in use, or it may be moved downwardly a limited distance so that the bar may swing freely laterally past the edge as the blade is being stropped or honed or cleaned and dried. The preferred form of guard comprises a serrated guard bar having resilient side arms mounted on the ends of the razor blade for a limited sliding and swinging movement, and it may be held fixed in a guarding position by means of the clamping side arms and a hook engaging the blade edge so that the guard may swing only when moved into the stropping position. The blade may be locked in place by means of a plunger mounted on the handle which is so constructed and arranged that the plunger may be pushed into contact with one or the other of two shoulders on the blade to hold it securely in either of its two operative positions. This plunger is preferably moved by means of a screw-threaded sleeve which is so arranged that it is unnecessary to move the sleeve but a short distance to release the plunger and move it to the other locking position. This movement of the plunger is preferably limited so that it cannot be accidentally removed from operative relation with other parts of the device. This invention is equally applicable to a razor blade which is permanently fastened in place in a holder or to a thin wafer like blade which may be removably mounted in a holder and replaced when desired.

Referring to the drawings which illustrate one embodiment of my invention, and in which like reference numerals indicate like parts:

40 Figure 1 is a sectional view, partly in elevation, showing the razor blade in the stropping position and the guard in the shaving position;

45 Fig. 2 is a side elevation, with parts removed, corresponding with Fig. 1, but with the guard located in the stropping position;

Fig. 3 is a side elevation, corresponding with Fig. 2, in which the blade and the guard are in the shaving positions;

50 Fig. 4 is a cross section on the line 4-4 of Fig. 2 showing the mounting of the blade in the holder;

Fig. 5 is an end elevation of the blade and the holder, with the guard and the blade in the stropping positions; and

Fig. 6 is an end elevation showing a holder arranged to carry a thin wafer like blade.

In accordance with my invention, I provide a handle 10 which is provided with a tapered portion terminating in two yoke like arms 11 between which the razor blade 12 is pivotally mounted for moving from a hoe-like shaving position, as shown in Fig. 3, to a stropping position, as shown in Fig. 1.

65 For conveniences of manufacture, I make

the blade 12 separate from its holder 13, and I provide the latter with a U-shaped portion 14 which is so shaped and constructed that it will fit closely between the yoked arms 11 and be fastened thereto by a pin 15. 70 The loop of the U-shaped member 14 extends outwardly beyond the ends of the arms 11 and is so arranged that the holder may be swung through an angle of 90 degrees.

The razor blade 12 is suitably mounted in 75 this holder 13 between the arm 16 on one side and the arms 17 and 18 on the other side, which are formed integral with the part 14 of the holder and extend in such a direction that the blade will lie at an appropriate 80 angle, such as 50°, to the center line of the handle. As shown in Fig. 2, the arm 16 extends substantially the length of the razor blade; while the arms 17 and 18 comprise two separated portions, as illustrated in Fig. 85 1, formed by bending downwardly the two metal pieces which are outside of the U-shaped portion 14.

In the construction shown in Fig. 4, the 90 razor blade 12 is set rigidly between the holding arms. If, however, it is preferred to use a thin wafer like blade which may be readily removed from the holder, I may employ the construction shown in Fig. 6, in which the arms 19 and 20 corresponding 95 with the arms 16, 17 and 18 are provided at their lower ends with up-turned members 21 and 22 of resilient material, which are so spaced that they will clamp against a thin blade inserted between them and hold 100 the blade firmly in position.

One simple means of locking the razor blade in either of its operative positions comprises a plunger 25 arranged to be moved into contact with different portions of the blade which are 90 degrees apart, relative to the pivotal supporting pin 15. As shown, the plunger may be slidably mounted within a central passage into the handle 10. The plunger is tapered at the end adjacent the blade to a thin portion 26 arranged to slide between the two flat yoked members 11. The end surface 27 of the portion 26 of the plunger is flat and adapted to engage one of the plane shoulders 28 on the sides of the 110 holder 13, when the blade is in the position shown in Fig. 1. When the blade has been turned into the position shown in Fig. 3, the end 27 will then engage the flat end 29 of the loop 14 of the holder. Since the contacting surfaces of the plunger and the blade are parallel planes, then if the plunger 25 is held from moving, the blade will be rigidly fixed, as desired.

Various operating means may be provided 125 for moving the plunger 25 back and forth and to hold the plunger locked against either one of the shoulders 28 and 29 of the holder and thus maintain the blade rigidly in the stropping or the shaving position. One 130

simple plunger operating device as illustrated, comprises a sleeve 32 which is internally threaded at 33 to turn upon the threaded portion 34 of the reduced end 35 of the handle 10. The sleeve 32 is connected to the plunger 25 by means of a web-portion 36 within the sleeve which is threaded onto the end portion 37 of the plunger. The threads 34 and 37 are preferably arranged in opposite directions, one right handed and the other left handed, so that the plunger may be moved the desired distance by a slight motion of the sleeve.

In order to prevent turning the sleeve 32 too far outwardly and thereby accidentally disconnecting it from the handle, I provide a cap 39 which is screwed into the internally threaded portion 40 of the sleeve 32. This cap is provided with a slot 42 or other means which makes it easy to remove the cap when desired for adjusting the parts of the razor.

It will therefore be seen that when the sleeve 32 is turned in such a direction as to move the plunger 25 outwardly, the plunger will strike the inside of the cap 39 soon after the opposite end 27 has been released from the shoulder 28 of the blade holder. Likewise the threaded portions are so arranged and assembled that the plunger may be released from the shoulder 28 and the razor turned through 90 degrees to the shaving position, after which the plunger may be moved forward sufficiently to bring the end 27 into engagement with the shoulder 29 of the holder 13, this shoulder 29 lying also at 90 degrees from the plane of the shoulder 28. The outside surfaces of the handle 10 and the sleeve 32 may be knurled or otherwise constructed to provide a firm hand hold.

The guard for the razor is preferably mounted on the razor in such a manner that the guard bar may be normally positioned laterally of the blade edge to protect the user of the blade, or the guard may be moved downwardly relative to the blade and permitted to swing freely from side to side past the edge of the blade as the latter is being stropped, honed or cleaned. One simple construction involving my invention comprises forming the guard with a cross bar 44 having teeth 45 and up-turned arms 46 and 47 fastened thereto, which are arranged to be pivotally and slidably mounted on the ends of the blade. These arms are preferably made of resilient material and bent inwardly to a slight extent so that the pressure exerted thereby on the ends of the blade tends to prevent the guard from being moved accidentally.

In order to hold the arms 46 and 47 properly located and prevent their removal except when desired and yet permit the guard to be moved through a limited distance when

the blade is to be stropped, I provide the blade holding parts 16, 17 and 18 with the lugs 48 and 49 on each end thereof. The upper ends of the arms 46 and 47 are also provided with enlarged heads 51 and 52. 70 The size of each head 51 and 52 and the distance between the lugs 48 and 49 are such that the head 52 cannot be drawn downwardly between the lugs but the guard may swing laterally to a slight extent. At each 75 end of the serrated edge 45 of the guard bar I provide the hooks 55 and 56 which are so shaped and arranged that when the guard is pushed upwardly these hooks will fit over the edge of the razor blade and prevent lateral swinging of the guard, as shown in Figs. 1 and 3. The arms 46 and 47 are of such length that when desired, the guard may be pulled downwardly against the resilient pressure of the arms 46 and 47 until the 80 heads 51 and 52 engage the lugs 48 and 49, as shown in Figs. 2 and 5, whereupon the guard bar 44 is sufficiently removed from the edge of the blade 12 so that the bar may swing freely back and forth past this edge 85 without touching it. In order that the operation of honing the blade may not wear the back of the guard to a detrimental extent, I provide the lugs 58 formed by bending back a thin strip of metal above each hook, as 90 shown in Fig. 5, and these lugs and the hooks 56 will ride on the hone and lift the guard bar 44 from contact therewith.

In view of the above description, it will now be seen that the operation of this device is very simple. The razor is normally placed in its case in the position shown in Fig. 1, and to put it in position for shaving it is merely necessary to turn the sleeve 32 in such a direction as to withdraw the plunger 25 from contact with the shoulder 28 of the holder 13. Then by grasping the blade, the latter may be turned through an angle of 90° so that it will be in a hoe-like position in which the central plane of the blade makes an angle of about 50° with the center line of the handle. By turning the sleeve 32 in the opposite direction, the plunger 25 is pushed into contact with the shoulder 29 of the holder 13, as illustrated 100 in Fig. 3. When it is desired to strop the razor, the blade is returned to the position shown in Fig. 1 and the guard 45 is pulled downwardly against the resilient pressure of the arms 46 and 47 until the heads 51 and 52 engage the lugs 48 and 49 on the ends of the blade holder. Thereupon the razor may be stropped or honed and the guard bar 44 will swing idly past the edge of the blade without touching it. To use the blade normally, the guard is shoved upwardly as far as it will go until the hooks 55 and 56 engage the corner edge portions of the blade and can hold the guard from swinging laterally. The plunger 25 automatically po- 105 110 115 120 125 130

sitions the blade and its holder correctly, owing to the fact that the contacting faces of the plunger and the holder are plane faces adapted to lie parallel with each other, 5 hence one need give no particular care when shifting the blade, except to swing it to an approximately correct position and then set the plunger against it, as well as to see that the guard is properly located. It will 10 also be obvious that the construction shown in Fig. 6 may be similarly employed and that the wafer blade may be removably inserted between the resilient members 21 and 22 and used the same as the blade shown 15 in Fig. 4.

Having thus described my invention, what I claim as new and desire to secure by Letters Patent is:—

1. A safety razor comprising a handle, a 20 blade mounted thereon to move from a hoe-like position to one substantially radial of the handle, a guard, and means to hold the guard protectively or non-protectively associated with the blade in either of said positions, whereby the blade may be used for shaving or may be stropped as desired.

2. A safety razor comprising a handle, a 30 blade pivotally mounted thereon to move from a transverse shaving position to a stropping position lengthwise of the handle, means to hold the blade fixed in either position, a guard, and means supporting the guard on the blade in a protective or in a non-protective association therewith for 35 both positions of the blade.

3. A safety razor comprising a handle, a 40 blade pivotally mounted thereon to move from a hoe-like position to a stropping position, manually adjustable means to hold the blade fixed in either position, a guard, and means to hold the guard protectively associated with the blade or to permit it to swing past the blade edge for the stropping operation.

4. A safety razor comprising a handle, a 45 blade pivotally mounted thereon to move from a shaving to a stropping position, means on the handle which is manually operable to lock the blade in either position and a guard pivotally and slidably mounted on the blade which is arranged as a protection on the blade edge during shaving or to be moved downwardly so as to swing laterally past the edge during stropping.

5. A safety razor comprising a handle, a 50 blade movably mounted thereon and a guard pivotally and slidably mounted so that it may be positioned laterally of the blade edge as a safety guard or it may be moved downwardly to swing past the edge during the stropping operation.

6. A safety razor comprising a handle, a 55 blade pivotally mounted thereon, means to hold the blade in a hoe-like shaving position or substantially radially of the handle for

the stropping operation, a guard having a cross bar to protect the user from the blade edge and arms adjacent to the ends of the blade, and means for pivotally mounting the guard on the blade which permits the cross 70 bar to be protectively associated with the blade or to be moved downwardly and swing past the blade edge.

7. A safety razor comprising a handle, a 75 blade mounted thereon, a guard therefor having a cross bar and two resilient arms pivotally and slidably mounted relative to the blade, and means to hold the cross bar immovable in a guarding position adjacent the blade edge or permit the guard to be 80 moved downwardly and swing laterally past the edge.

8. A safety razor comprising a handle, a 85 blade thereon and a guard resiliently, pivotally and slidably mounted on the blade which has a bar adjacent the blade edge and a hook arranged to engage the blade, said parts being so constructed and arranged that the guard may be moved downwardly to disengage the hook and permit the bar 90 to swing past the blade edge during stropping.

9. A safety razor comprising a handle, a 95 blade mounted thereon, a guard comprising a cross bar, resilient arms which engage the ends of the blade, and a hook adapted to engage the edge of the blade to hold the same immovable, and cooperating means on the guard and the blade which permits the guard bar to be moved downwardly to disengage 100 the hook from the blade and to swing laterally past the blade edge.

10. A safety razor comprising a handle, a 105 blade pivotally mounted thereon to move from a hoe-like to a stropping position, means to hold the blade in either position, a guard having a cross bar located adjacent the blade edge, arms mounted on the ends of the blade and a hook adapted to engage the edge of the blade, and means holding the 110 arms on the ends of the blade which permits limited swinging and sliding movements thereof, whereby the bar may stand in a guarding position or be moved downwardly to disengage the hook from the blade edge 115 and swing laterally past the same.

11. A safety razor comprising a hollow handle, a razor blade pivotally mounted on said handle to move from a hoe-like position, a guard movable with the blade, to a 120 stropping position, a plunger slidably on the handle to engage the blade in either position, and manually adjustable means on the handle to hold the plunger securely against the blade.

12. A safety razor comprising a hollow handle, a blade pivotally mounted thereon to move to two positions, a plunger slidably mounted within the handle to hold the blade in either position, and a sleeve 130

threaded on the handle and the plunger which is arranged to move the plunger in either direction.

13. A safety razor comprising a hollow handle, a razor blade pivotally mounted on said handle to move into a shaving or a stropping position, a plunger within the handle to engage the blade and hold it in either position, a manually adjustable operating member connected with the handle and engaging said plunger to move the same, and means to limit the outward movement of the plunger.

14. A safety razor comprising a hollow handle, a blade movable thereon from a hoe-like to a stropping position, a guard therefor, a plunger within the handle arranged to engage and hold the blade in either position, a sleeve threaded on the handle and the plunger to move the latter, and a cap on the sleeve to limit the outward movement of the plunger.

15. A safety razor comprising a handle, a razor blade pivotally mounted thereon and having two shoulders at about 90 degrees to each other, a plunger slidably mounted on the handle and adapted to engage one or the other of said shoulders, and a sleeve connected with the handle and the plunger by threads running in opposite directions so as to move the same rapidly.

16. A safety razor comprising a hollow

handle, a razor blade pivotally mounted thereon which has two shoulders, a plunger slidable within the handle and adapted to engage either of said shoulders and hold the blade in either a shaving or a stropping position, screw-threaded means on the handle adapted to move the plunger towards and from the blade and a guard slidably and pivotally mounted on the blade which is adapted to guard the same during shaving or to be moved downwardly to swing freely past the edge during stropping.

17. A safety razor comprising a handle, a blade holder pivotally mounted thereon, a razor blade removable from said holder, means on the handle to lock the blade in either a shaving or a stropping position and a guard pivotally and slidably mounted on the blade and holder which is arranged to protect the edge of the blade or to move downwardly and swing freely past the blade during stropping.

18. A safety razor comprising a handle, a blade holder pivotally mounted thereon for movement from a shaving to a stropping position, resilient blade holding arms on said holder, a blade removably mounted therein, a guard for the blade edge and means to secure the holder in either of said positions.

Signed at New York, N. Y., this 29th day of June, 1925.
